UNITED STATES PATENT OFFICE.

WILLIAM C. GEER, OF AKRON, OHIO, ASSIGNOR TO THE B. F. GOODRICH COMPANY, OF NEW YORK, N. Y., A CORPORATION OF NEW YORK.

GAS-MASK.

1,364,104.

Specification of Letters Patent. Patented Jan. 4, 1921.

Application filed January 23, 1919. Serial No. 272,618.

To all whom it may concern:

Be it known that I, WILLIAM C. GEER, a citizen of the United States, residing at Akron, in the county of Summit and State 5 of Ohio, have invented certain new and useful Gas-Masks, of which the following is a specification.

This invention relates to respirator masks for protecting the wearer's eyes and breathing organs against fumes, gases, smoke and other contaminations of the atmosphere, and its general objects are to improve the sealing properties of the mask around the edges thereof, to provide a better mode of ventilating 10 the eye-pieces, to minimize the amount of dead air space, reduce the weight and cost and increase the comfort of wearing the mask.

Of the accompanying drawings,

20 Figure 1 is a side elevation, partly broken away, showing a preferred form of my improved mask.

Fig. 2 is a rear elevation thereof with the head-covering portion partly laid open at 25 the back.

Fig. 3 is a section on the line 3—3 of Fig. 2.

Fig. 4 is a section on the line 4—4 of Fig. 2.

30 In the drawings, 10 is a face cover made of any suitable impervious flexible material such as sheet rubber molded and vulcanized on a form and preferably having the usual outer covering of stockinet indicated by the 35 shading in Fig. 1. 11, 11 are the transparent eye-pieces or windows therein, and 12 is an opening in front of the wearer's mouth leading to the atmosphere through a suitable check-valve or exhaling valve 13 inclosed in 40 a metal casing 14. A common practice heretofore has been to provide a cast metal fitting formed with both an air inlet and an air outlet, said inlet branching upwardly through a pair of flexible or other clarifying 45 tubes to the spaces back of the eye-pieces, so that the air which is breathed in through the filter by way of the air-inlet passage will avoid or remove the condensation of moisture on the inner side of the eye-piece 50 glasses, known as fogging. This metal fitting was somewhat clumsy and added weight and expense to the mask. My present improvement includes the use of a flexible intake pipe on the outer side of the mask lead- 55 ing into the interior thereof independently

of the air outlet structure and making a joint with the face covering at a point closely adjacent to and preferably between and slightly above the middle of the eye-pieces, from which point it may lead in an 60 anterior direction to one side of the face covering (to which side it may also be attached) where it is adapted for connection with a pipe leading over the wearer's shoulder to a filter strapped on his back, but this 65 upward, lateral, rearwardly-leading disposition of the anterior part of the inlet pipe, as well as other details, may be varied or omitted. The anterior section of the air inlet pipe having this construction and arrangement is represented at 15, and a loop or strap 16 is shown for securing it to the upper side portion of the face cover. A similar pipe is shown but not claimed in my prior application Serial No. 254,195, filed 70 September 16, 1918, and this case is a continuation of said application as to that feature. The usual corrugated breathing pipe leading to the air filter or canister may be connected to the rearwardly-directed end of 80 the pipe 15, but is omitted from the illustration as being a well-known feature. It will be observed that a flexible pipe having this disposition allows the mask to be worn with increased comfort, provides a lighter, more 85 compact and less expensive construction than heretofore, and permits a reduction in the size of the dead air space within the mask, since the interior portion of the air 90 passage may be reduced to a minimum. This interior portion is formed by the part of the face cover 10 between and above the eye-pieces 11 as its front wall, while its rear wall is constituted by a flexible piece 17 of sheet material such as soft rubber having its 95 edges secured to the face cover except along two arcs of the eye-pieces 11, where a pair of slit-like openings 18 impinge upon the rear surfaces of the glasses, these openings forming the clarifying or anti-fogging air 100 inlets to the interior of the mask. The joint between the face cover 10 and the flexible pipe 15 is preferably a flexible, cemented and vulcanized joint formed around the mouth of said pipe.

The upper margin 19 of the face cover 10 embracing the wearer's forehead serves to seal the breathing space of the mask at the upper end thereof, and the rest of said space is sealed by the rear margin 20 of said face 110

cover, passing down along the cheeks in front of the ears and under the chin. Formerly the straps or harness attached to these margins, and the construction of the margins themselves, especially at the cheeks and temples, has been such that these margins as a whole would not effectively seal the breathing space, owing largely to the non-conforming character of the margins in relation to the usual flat or hollow portions of the face, and the tendency to produce buckling of some portion or portions of said margins owing to the direction of pull of the head straps.

15 For improving the sealing, I have shown two expedients which may advantageously be used co-operatively in combination as shown, although either may be employed separately without departing from the scope 20 of my invention.

One expedient consists in a means for producing perpendicular inward pressure of the mask margins at the sides of the face and especially in the temporal regions, which are 25 hollow or at least flat in most faces so that no inward sealing pressure is produced at these portions by a straight pull exerted on a marginal member of the ordinary construction, even though such member may be thickened 30 or beaded. To produce such perpendicular inward pressure as the resultant of longitudinal pull exerted on the marginal portion or portions of the mask I provide suitable pads 21 located principally in the rear 35 marginal portion 20 but also partly in the margin 19 in the regions of the temples. These pads may be of any suitable construction, but are preferably hollow as shown, their inner walls being convexly molded in 40 the main rubber member of the mask and covered with substantially flush vulcanized, soft-rubber pieces 22 for transmitting the straight pull on the margins. The pads are also preferably longest in a substantially 45 vertical direction as indicated.

The other sealing expedient consists in the use of a pair of elastic, flexible, harness straps such as 23, 24 which pass respectively over the top and around the back of the 50 wearer's head from opposite points on the mask in the region of the temples, and hence exert their pull upon the rear and upper edges of the face cover 10 in directions substantially at right-angles. Consequently 55 there is no resultant longitudinal force on

either margin 19 or 20 tending to cause buckling of said margin, and the sealing is improved. These straps act both individually and co-operatively upon said margins and the pads 21 to produce the described perpendicular sealing pressure of said pads against the hollows of the face. A third stabilizing and weight-sustaining strap 25 is preferably provided, passing from front to rear over the wearer's head to connect the middle portions of the forehead-embracing margin 19 and of the straps 23, 24, all these members being permissibly made of soft vulcanized rubber in one piece with the main member of the face cover. The open spaces 60 may be suitably filled in, as with stockinet 26, so that the entire top structure forms a hat, and in order that some adjustment may be made for size, I prefer to divide the rear portions of the straps 24 and 25 in a median vertical plane and provide eyelets 65 27 and a lacing 28 to connect the divided edges.

I claim:

1. A gas mask comprising an impervious 80 face cover having a top flexible margin adapted to embrace the wearer's forehead and a rear flexible margin adapted to embrace the cheeks and chin, a strap connecting the temporal portions of said face cover 85 around the back of the head and adapted to exert a longitudinal pull on the first mentioned margin, and another strap connecting said temporal portions over the top of the head and adapted to exert a longitudinal 90 pull on the second mentioned margin and a pair of inwardly convex sealing pads incorporated in said margins in the region of the temples, the inner surfaces of said pads being integral with the inner surface of said 95 face cover.

2. A gas mask comprising a face cover having a flexible top, forehead embracing margin and a flexible rear face embracing margin substantially at right angles thereto, 100 head straps lying approximately in extension of said margins; a pair of inwardly convex sealing pads incorporated in said margins at the temples, and a flexible, external air inlet pipe extending forwardly and laterally across the temple and forehead of said face cover and attached thereto. 105

In testimony whereof I have hereunto set my hand this 20 day of January 1919.

WILLIAM C. GEER.
